CLAIM

The ornamental design for a golf training mat, as shown and described.

DESCRIPTION

FIG. 1 is a top plan view of a first variant of a golf training mat;

FIG. 2 is a top plan view of a second variant of a golf training mat;

FIG. 3 is a top plan view of a third variant of a golf training mat;

FIG. 4 is a top plan view of a fourth variant of a golf training mat;

FIG. 5 is a left side elevation of the golf training mat of FIG. 4, with the right side elevation being a mirror image of the left side elevation;

FIG. 6 is a front elevation of the golf training mat of FIG. 4; and,

FIG. 7 is a top, front, left side isometric view of the golf training mat of FIG. 4.

The design is the perimeter shape of the golf training mat shown in solid lines in the FIGS. 1 to 3 and the shape of the golf training mat shown in solid lines in FIGS. 4 to 7. The portions shown in stippled lines do not form part of the design.
